MIXED LIQUID HEATER AND SEPARATOR

Raymond S. Sullivan, Redondo Beach, Calif.

Application April 14, 1947, Serial No. 741,209

3 Claims. (Cl. 122—149)

1

This invention relates to means for treating liquids, and particularly pertains to a mixed liquid heater and separator.

In various industries it is desirable to treat mixed liquids, such as oil and water, in order to separate and recover the oil from the mixture. This is particularly true in connection with the production of crude oil in which water is often mixed with the oil. It is desirable to provide simple and effective means whereby mixed fluids may be passed rapidly through treating apparatus and within which the fluids are separated and the valuable fraction thereof recovered in a continuous operation. It is the principal object of the present invention, therefore, to provide a treating furnace through which mixed fluids, such as oil and water, can be passed and within which these fluids are heated while the fraction, such as oil, is washed, and after which the water is driven off to permit the oil to be recovered continuously.

The present invention contemplates the provision of a heater of the horizontal tubular type into which mixed fluids, such as oil and water, may be introduced and circulated in heat exchange relationship to a combustion chamber and flue pipes while the fluid is heated and the water is driven off.

The invention is illustrated by way of example in the accompanying drawings in which:

Figure 1 is an end view showing the heater with which the present invention is concerned.

Fig. 2 is a view in longitudinal vertical section through the heater as seen on the line 2—2 of Fig. 1 and shows the details of construction of the heater.

Fig. 3 is a view in transverse vertical section through the fire-box of the heater as seen on the line 3—3 of Fig. 2.

Fig. 4 is a view in transverse vertical section and elevation as seen on the line 4—4 of Fig. 2 and shows the relation between the baffle walls and the flue tubes.

Fig. 5 is a view in vertical section along the line 5—5 of Fig. 2 and shows the arrangement of tubes and a wall at the stack end of the heater.

Referring more particularly to the drawings, 10 indicates an outer cylindrical shell, at one end of which is formed a bolting flange 11 to receive a transverse tube plate 12. The transverse tube plate extends entirely across the end of the shell 10 and is held in position by an annular flange 13 of angle section which is secured in place by bolts 14. This flange serves as a mounting for a flue outlet structure 15 which has a

2

cylindrical wall section 16 agreeing substantially in radius with that of the shell 10, a transverse wall section comprising opposite horizontal lengths 17, and an intermediate semicylindrical portion 18. The plane of the wall sections 17 is materially lower than the horizontal center plane of the shell 10, for a purpose to be herein-after described. The outer edge of the flue structure 15 inclines upwardly and outwardly and is closed by a removable end plate 19. This plate is held in position by bolts 20 and nuts 21. A flue opening 22 is formed through the top of the section 16 of the flue outlet 15 and is in register with a stack 23 of a desired height. This stack 15 is secured in position by a saddle flange 24, which flange is fastened to the portion 16 by bolts 25 and nuts 26.

A circular opening 27 is formed through the end plate 12, the longitudinal axis of which opening lies in the horizontal plane of the wall sections 17 of the flue outlet. The wall section 18 is concentric with the center of the opening 27 and is spaced a distance therefrom. Extending horizontally and inwardly through the opening 27 of the tube sheet 12 is a fire tube 28. This tube is welded into the tube sheet 12 at one end and is welded into an end wall 29 of a combustion chamber 30 at its opposite end. The combustion chamber 30 is formed by a cylindrical shell 31 which is welded at one end to the end wall 29 of the combustion chamber 30. The opposite end of the shell 31 is closed by a dome 32 which is here shown as welded in position. The outside diameter of the combustion chamber shell 31 is materially less than the inside diameter of the outer shell 10. Mounted at the outer end of the fire tube 28 and beyond the end of the tube sheet 12 is a fuel burner 33 which directs a flame of fuel longitudinally of the tube sheet 12 and into the combustion chamber 30. A plurality of flue pipes 34 extend through openings in the tube sheet 12 and the end wall 29 of the combustion chamber. These flue pipes are arranged in three horizontal rows as shown in Fig. 5 of the drawings and are substantially uniformly spaced with relation to each other in the area defined by the flue outlet structure as shown in Fig. 5. The shell 31 of the combustion chamber 30 is supported upon a skid structure 35 which is secured to the lower side of the shell 31 and rests against the lower portion of the outer shell 10. This skid supports the shell 31 so that when the flue structure 15 and the ring 13 are removed from the end of the shell 10 the fire tube as well as the

flue tubes and the combustion chamber may be withdrawn bodily from the shell 10.

The end of the shell opposite from the tube sheet 12 is here shown as closed by a dome 36 which is welded in place. This dome is spaced from the end of the combustion chamber dome 32 a distance substantially equal to the spacing of the shell 10 from the shell 31. Formed through the dome 36 at diametrically opposite sides of the vertical center thereof is an oil inlet opening 37 and a wash tank opening 38. Pipe couplings 39 and 40, respectively, are fixed into these openings. Attention is directed to the fact that the openings are in a horizontal plane materially lower than the horizontal plane occupied by the longitudinal axis of the shell.

Secured along the horizontal center plane of the shell 10 and to the inner face of the dome 36 is a horizontal flange 41. The top of this flange is in alignment with two opposite angle members 42 and 43 which are secured to the inner face of the shell 10 and extend throughout the length of the shell to the tube sheet 12. Fixed to the opposite sides of the combustion chamber shell 31 and around the end of the dome 32 is a horizontal partition flange 44 which rests upon the angle flanges 42 and 43 and divides the space around the combustion chamber into an annular upper circulating space 45 and an annular lower circulating space 46. Extending from the end wall 29 of the combustion chamber 30 and lying in the same plane is a horizontal baffle plate 47. This plate extends horizontally and is supported at its opposite edges upon the angle members 42 and 43. Adjacent the opposite end of the plate 47 from the combustion chamber and spaced from the tube sheet 12 is a transverse supporting angle 48. This supports the free end of the baffle plate 47 and provides a circulation throat 49 through which liquid may pass upwardly as it flows through the heater, as will be hereinafter described. The baffle plate 47 is positioned between the fire tube 28 and the intermediate horizontal course of flue pipes 34. The transverse supporting member 48 is angle-shaped and is disposed with one vertical leg extending downwardly. This leg is formed with notches 50, as shown in Fig. 4 of the drawing. These notches act as oil spreaders and tend to insure that the flow of liquid will be distributed horizontally as the liquid flows upwardly through the opening 49 and into a circulation space 51 which occurs between the lower baffle plate 47 and an upper baffle plate 52. The upper baffle plate 52 is parallel to the baffle plate 47 and is supported from opposite edges of the shell 10 in a plane between the upper row of flue pipes 34 and the intermediate row of flue pipes 34. The upper baffle plate 52 extends entirely from the tube sheet 12 to the end wall 29 of the combustion chamber 30. Continuations thereof, as indicated at 53, extend along opposite sides of the combustion chamber shell 31 and are parallel to the baffle plate members 44 which are supported upon the angles 42 and 43. The baffle plate continuations 53 are supported by inwardly extending flange members 54 which are welded to the inner surface of the shell 10 and form a fluid seal with the extensions 43 and also with the body of the baffle plate 52. This creates fluid passageways 55 and 56 along the opposite sides of the combustion chamber shell 31 and between the baffle plate extensions 44 and 53. The baffle plate extensions 53 are shown in Fig. 2 of the drawing as terminating short of the end of the combustion chamber 30.

Thus a return passageway 57 occurs around the end of the baffle plate extensions 53 and into a circulation space 58 thereabove. The space 58 represents a sector of a circle defined along its outer perimeter by the upper portion of the shell 10. The upper course of flue tubes 34 occurs within this circulation space. The treated oil is drawn off from the shell through an outlet coupling 59 which extends through the top of the wall of the shell 10 adjacent to the tube plate 12. A suitable conduit connects the coupling 59 with a liquid separator. The heavy material incident to the operation is drawn off through a drain connection 60. The entire heater structure is supported upon legs 61 to hold the shell 10 at a desired and convenient elevation above the floor.

In operation of the present invention a controlled flow of mixed oil and water is introduced through the oil inlet coupling 39 into the space 46 around the combustion chamber. Water from a wash tank is introduced through a coupling 40 into the space 46. The liquid fills the space 46 and envelopes the lower half of the combustion chamber shell 31 occurring beneath the baffle extension 44. The oil also envelopes the fire tube 28 and rises to the level of the horizontal baffle plate 47. The oil then flows upwardly through the circulation opening 49 at the end of the baffle plate 47 which is spaced from the tube sheet 12. The flow from the couplings 39 and 40 and within the lower half of the shell is in the direction indicated by arrow *a* in Fig. 2. After the liquids pass through the circulation passageway 49 a counter-flow of the liquid is established in the direction of the arrow *b* as indicated in Fig. 2, and the fluid fills the space 51 and continues outwardly in the space 55 between the baffle extensions 44 and 53. A return flow then takes place in the space 57, as indicated by the arrow *c*, and the liquid continues horizontally through the shell 10 in the direction of the arrow *d* and within the circulation space 58. During this time it will be obvious that the fire tube 28, the combustion chamber 30, and the flue pipes 34 are all submerged within the liquid being treated. While in this condition the burner 33 is ignited to direct a jet of combustion material horizontally and into the fire tube 28 in the direction of the arrow *e*. This fuel and the products of combustion fill the enlarged combustion chamber 30 and then return in a counter-direction, as indicated by the arrow *f*, through the various tubes 34. The products of combustion flow outwardly from the ends 55 of the flue pipes which pass through the tube sheet 12 and into the flue outlet structure 15. The products of combustion then pass upwardly through the stack 23 as regulated by a damper 23'. The treated liquid then passes outwardly through the outlet coupling 59 and may thereafter be handled as desired. The residue which may accumulate in the bottom of the shell 10 is drawn off through the connection 60.

It will be seen from the foregoing description that the liquid to be treated flows initially in a counter-direction to the travel of the products of combustion in the fire tube and in a counter-direction through the flue tubes which occur in the space between the horizontal baffle plates 47 and 52. This insures maximum efficiency of heat exchange. In addition to this flow the fire tube occurring within the space 58 will also be in heat exchange relationship to the liquid flowing toward the outlet connection 59. It will also be noted that the combustion cham-

ber 30 is submerged completely within the liquid to be treated. When it is desired to clean the structure or to replace the fire tube or the flue pipes the flue outlet structure is removed from the end of the shell 10 by unfastening the bolts 14. The tube sheet 12 will then be free so that the tube sheet, together with the fire tube 28, the flue pipes 34, and the combustion chamber 30, may be bodily withdrawn as a unit while the skid 35 will slide along the inner lower face of the shell 10.

It will thus be seen that the structure here disclosed is simple in design and provides a heating unit which may be easily inserted into a shell or removed bodily therefrom, and which unit when in position will form passageways along which a liquid to be treated may pursue a sinuous path of travel in heat exchange relationship with the various elements of the heating unit.

While I have shown the preferred form of my invention as now known to me, it will be understood that various changes may be made in combination, construction and arrangement of parts by those skilled in the art, without departing from the spirit of the invention as claimed.

Having thus described my invention, what I claim and desire to secure by Letters Patent is:

1. A liquid heater and separator of the character described, comprising an outer tubular shell, means closing one end of said shell, a tube sheet for closing the opposite end of said shell, a heat exchange unit including said tube sheet and comprising a fire tube extending through the tube sheet and longitudinally of the shell, a combustion chamber at the inner end of said fire tube and conforming to the contour of the interior of the shell while being spaced from the walls thereof, a plurality of flue pipes extending longitudinally from the combustion chamber and through the tube sheet whereby products of combustion delivered to the combustion chamber through the fire tube may escape through the flue pipes, horizontal baffle plates assembled with the heat exchange unit and spaced vertically from each other within the shell, and cooperating means carried on the inner wall of the shell to register with said baffle members to divide the shell into a plurality of horizontal passageways intermediately of said baffles whereby the heat exchange unit may be withdrawn bodily from the tube sheet end of the shell.

2. A fluid heating structure of the character described comprising an outer tubular shell horizontally disposed, a dome closing one end thereof, a combustion chamber mounted within the shell adjacent to the closed end thereof, said combustion chamber having an outer wall spaced from the inner wall of the shell and its dome, means supporting the combustion chamber in said spaced position, a fire tube of relatively large diameter communicating with said combustion chamber and extending longitudinally of the shell to its open end, a tube sheet through which the outer end of said fire tube extends, a fuel burner disposed adjacent to the open end of the tube sheet and projecting a flame of combustible material into and longitudinally of the fire tube, a plurality of flue pipes communicating with the combustion chamber and leading through the tube sheet, said pipes being of smaller diameter than the fire tube and being arranged in a series of horizontal courses within the shell, a partition wall extend-

ing between the fire tube and a superimposed course of flue pipes, said wall extending horizontally around the perimeter of the combustion chamber, cooperating means extending inwardly from the wall of the shell and being engaged by the partition wall to divide the shell into upper and lower longitudinally extending passageways, means for introducing a liquid to be treated into the lower of said passageways adjacent to the combustion chamber, a throat formed through the partition wall adjacent to the tube sheet for permitting the fluid to be treated to pass into the upper passageway of the shell, and an outlet conduit for conducting the treated fluid from the shell.

3. A mixed liquid heater and separator comprising an outer cylindrical shell disposed horizontally, a closure for one end of said shell, a tube sheet detachably secured over the opposite end of the shell, a fire tube extending through the tube sheet and extending longitudinally within the shell, a fuel burner disposed at the outer end of said fire tube and designed to project a jet of combustible fluid into said fire tube and longitudinally thereof, a combustion chamber with which the inner end of the fire tube communicates, said combustion chamber including a transverse wall through which the inner end of the fire tube passes and a cylindrical shell closed at the opposite end from the wall and being disposed in spaced relation to the inner wall of the outer shell whereby a fluid circulation space will occur around the combustion chamber, a plurality of flue tubes extending through the transverse wall of the combustion chamber and through the tube sheet, said flue tubes being arranged in a series of parallel horizontal rows across the section of the outer shell, a horizontal partition extending longitudinally of the outer shell and between the fire tube and a row of flue tubes, portions of said partition extending horizontally around the combustion chamber, means between the outer edges of the partition and its extensions for forming a fluid joint with relation to the wall of the outer shell, a second partition wall horizontally disposed between the previously mentioned row of flue tubes and an upper row of flue tubes, said second partition extending from side to side of the outer shell and along opposite sides of the combustion chamber whereby a fluid space will occur between the two partition walls and a parallel fluid space would occur between the upper partition wall and the top of the outer shell, a throat formed through the lower partition near the tube sheet, means introducing fluid into the outer shell in the space below the lower partition and means for withdrawing fluid from the shell and directly from within the upper fluid space, a flue outlet structure detachably secured at the end of the tube sheet and in communication with the flue pipes, and a stack communicating with said outlet connection.
